UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

WEB-RENEWING DEVICE.

1,319,448.

Specification of Letters Patent.

Patented Oct. 21, 1919.

Application filed February 8, 1917. Serial No. 147,427.

To all whom it may concern:

Be it known that I, HENRY A. WISE Wood, a citizen of the United States, residing at New York, in the county of New York and State of New York, have invented a new and useful Web-Renewing Device, of which the following is a specification.

This invention relates to mechanism for connecting a fresh web to an expiring web 10 in a printing press without stopping the press or slacking its speed.

The principal objects of the invention are to provide means actuated from the paper roll itself for controlling the connection of 15 the end of the fresh web with the end of the expiring one and severing the latter from the stub while the press is operating at full speed; to provide improvements in the mechanism by which the operation is controlled; and to provide an improved actuating cam supported by the web roll.

Further objects and advantages of the invention will appear hereinafter.

Reference is to be had to the accompanying drawings, in which—

Figure 1 is a side elevation of the end of a printing press showing a preferred embodiment of this invention applied thereto;

Fig. 2 is an elevation of the same looking 30 from the front of the press, and showing the web roll broken away to illustrate the controlling arms;

Fig. 3 is a side view showing the position 35 of the parts illustrated in Fig. 1 with parts in front omitted, or in other words, a section through the shafts just behind the frame and showing the wiring diagrammatically;

Fig. 4 is a similar view of the lower web roll on enlarged scale showing another position of the parts;

Fig. 5 is a front view of the parts shown in Fig. 4;

Fig. 6 is a perspective view of the actuating cam on the end of the web roll, and

Fig. 7 is a perspective view of the controlling cam for the surface of the web roll.

This invention relates to that type of web renewing devices in which a fresh web roll is located in bearings on the press either 50 above or below the expiring roll and is brought up to web speed by mechanism, not shown herein. In that type of machine the expiring web is brought into pasting contact with the surface of the fresh web by a

bodily moving pasting roller which engages 55 the expiring web and moves it. One of these rollers is provided for each of the conditions that have to be met, namely, the application of one expiring web to a new web roll above and the application of the other expiring 60 web to a roll below.

The two pasting rollers are connected so as to move together in either direction. When either web is about exhausted both of these rollers are moved so that one of them 65 comes into contact with the outside of the web and forces it into contact with the pasted fresh web roll. The motion of the two rollers in one direction is for the purpose of using one of them, and the motion in 70 the other direction for using the other. In either case the roller that is to be used is brought close to the web and held there until the fresh web roll rotates into a position in which the pasted portion registers 75 with a line along which the fresh web is to be pressed against it. Then connections are operated for releasing the pasting roller from this position and causing it to press the expiring web against the fresh web roll. 80 This, of course, in view of the timing just described, brings the old web just in advance of the line on which it is to be severed into contact with the surface of the new web that has been pasted or glued. It is secured to it 85 by the pressure of the roller on the back of the old web. The severing of the old web is then performed automatically. The operation described in this paragraph is the same as that set forth in my prior application 90 for patent on web renewing device for printing presses filed September 19, 1914, Serial No. 862,469, and is described herein because this invention is shown in the drawings as applied to a machine operating in that way. 95

Referring now to the drawings, the mechanism is shown as mounted on the frame 1 of a printing press, only the end of which is shown. In bearings on the brackets 2 with which this frame is provided a fresh web 100 roll 3 is located, one for each deck of the press. This web roll is provided with a spindle 4 and an actuating cam 5 is located on each end. In my above mentioned application this cam is fixed to the spindle, but in 105 this case it is shown as having prongs 7 which enter the end of the roll between the layers of paper thereon. The cam therefore

is easily secured in any desired position. The expiring web roll is indicated at 6, and in these drawings it is the fresh upper web roll 3 that is being connected up with the 5 expiring web from the lower roll although of course the opposite operation is also performed in the same way.

The following mechanism shown in my above mentioned application is also shown 10 herein. Between each two decks of the press the shaft 11 is provided with a double toothed clutch 48 operated by a hand lever crank 29 fixed to a shaft 56. The oppositely facing teeth of this clutch coöperate with 15 teeth on a pair of bevel gears 46, both meshing with a bevel gear 47. This gear is supported by a shaft which is provided with a worm 45, which worm meshes with a worm wheel 44 on a shaft 40. On this shaft is a 20 bevel gear 41 which meshes with a corresponding bevel gear 42 on a vertical shaft 43. The shaft 40 and gears 41 and 42 are duplicated above.

Each shaft 40 carries two gears 39 each 25 meshing with an oscillating supporting member, in the form of a segment 36, one pair for each of the two web rolls. Each of these segments is pivoted on a stud 58 on the frame 1 and carries a pivoted arm 30 37 in which the spindles of pasting rollers 38 are journaled. Thus it will be seen that the two parallel shafts 40 are caused to rotate simultaneously in either direction and the pasting rollers 38 moved up or down 35 by manipulation of the hand lever crank 29.

The pasting roller arms 37 are normally held against stops 49 on the segments 36 by means of springs 50 except while in pasting position. When either pair of segments approaches the pasting position, adjustable pin stops 51 on the arms 37 come into contact with stop levers 52 pivoted to the frame 40 of the machine at 53. Each stop lever 52 is held, by means to be described, in such 45 position as to hold the arm 37 and compress the two springs 50. The latter are ready to propel the roller 38 against the fresh web roll when the two stop levers 52 are released from the position shown in Fig. 1 50 and thus apply the roller with spring pressure against the web.

Both pairs of segments 36 are stopped in the correct pasting position by means of two pins 54 on one of the segments coming 55 into contact, at the end of the motion of that segment, with a throw-out lever 55 attached to the shaft 56 of the hand lever crank 29. This throws out the clutch and stops further motion in that direction.

60 On the same stud 58 on which each segment 36 is pivoted, a toothed segment 57 is pivoted independently of the segment 36. The two segments 57 mesh with the teeth on opposite sides of a reciprocating rack bar 65 59. A spring 68 holds the rack-bar 59 to

the right, thus drawing the two segments 57 in the same direction and keeping the ends of the two cam levers 52 in the recesses 60 unless the segments 57 are forced to the left positively. In that event the 70 parts will assume the position indicated in dotted lines in Fig. 4. Each segment 57 is provided with a recess 60 in one edge for receiving the end of the stop lever 52 and holding it in the position shown in 75 Fig. 1. It also has a cam incline 61 down which the end of the lever 52 is adapted to slide when the segment 57 is drawn back to release the cam lever. To the opposite end 64 of each segment 57 is pivoted a trip 80 lever 62 having a cam roller 63 thereon. This cam roller is adapted to be operated by the cam 5 on the end of the web roll spindle.

As so far described the operation is the 85 same as in my above mentioned application. According to this invention a catch 67 holds the lever 62 in such position that the roller 63 is normally out of contact with this cam. In order to control the operation 90 of these elements a cam 10 is mounted on the fresh web roll. This is shown as having a thin flange 10^a adapted to fit the circumference of the web roll and it is shown as being mounted by slitting one of, or a few 95 of, the top layers of the web roll and inserting the flange so that the cam appears on the web roll as a hump. It will be understood, of course, that it can be inserted under the top few layers if desired 100 or it can consist of a projection formed of any desired material, such as card-board, a pad of paper or the like, placed upon or beneath the outside layers of web roll. It is placed at a definite distance from the 105 end thereof as will appear.

This cam is designed to operate a roll 14 located on a lever 12 which is mounted to swing freely on a shaft 13 carried by the bracket 2. On this shaft 13 is also 110 fixed an arm 16 which is provided with two electrical contacts 15 on opposite sides of the lever 12. On the arm 16 are two springs 17 pressing on opposite sides of the lever 12 and holding it normally in central position so as to keep the lever out of engagement with both of the contacts 15. This arm 16 is provided with two rollers 18, one of which is adapted to engage the upper web roll when used in connection therewith 120 and the other of which will engage the lower web roll when that is to be attached to the expiring web. The shaft 13 is provided with an operating arm 19 by which it can be turned into the several positions in which 125 it is to be used. Its normal position is shown in Fig. 1 and it can be swung from that either upwardly as shown in Fig. 3 or downwardly. In the present case it is shown as swung upwardly so that the right- 130

hand roller 18 engages the surface of the web roll and the roll 14 is in the path of the cam or hump 10.

One of the contacts 15 is connected with 5 one end of an electro-magnet 20 for the upper roll, and the other with a similar electro-magnet for the lower roll. The other terminal of each of these electro-magnets is connected with the arm 12 so that when 10 the arm 12 is moved backwardly from the position shown in full lines in Fig. 3 it will connect up one of the electro-magnets 20, attract its armature 22 and release the catch 67. This releases the trip lever 62 and 15 a weight 65 with which it is provided swings it over into the position shown in Fig. 4.

It will be understood that, as in my application above referred to, when this lever 62 is released from the cam 5 and allowed to move back into the position shown 20 in Fig. 3 the spring 68 will force the segments 57 back to the right and force the stop-levers 52 up the inclines 61 until they are locked in the position shown in Fig. 3. 25 The oscillating segments 36 are shown in Figs. 1 and 3 at one end of their oscillation. When they move back to the opposite limit of their motion they assume the position shown in dotted lines in Fig. 3. 30 For the purpose of severing the web a thin knife 69 is controlled by a pin 74 on the top of the rack bar 59. The cutting action occurs as soon as the pin 74 moves back, preferably as described in my above 35 mentioned case.

The operation of the features of this invention is as follows: When it is desired to attach the fresh web to the expiring one the arm 19 is thrown up so that one of the 40 rollers 18 comes into contact with the fresh web roll above or below which has already been brought up to web speed. This action brings the roller 14 into the path of the cam 10. At the proper time this cam causes the 45 lever 12 to move away from the paper roll surface and form an electrical contact between the lugs on the levers 12 and 16. This causes one magnet 20 to draw the catch 67 away from the lever 62. The counter-weight 65 on this lever causes it to drop and the roller 63 to come into contact with the cam 5. It will be understood that the weight holds the lever down in this position during the operation of this cam. This cam 50 controls the operation of cutting by the knife 69 and pasting by one of the rollers 38. After the web is connected the lever 62 is swung back by hand until caught by the catch 67.

60 The other operations performed are conducted as in my above identified application preferably.

The parts are operated automatically and timed correctly in synchronism with the operation of the press, and the control of the

actuation of the parts is provided from the web roll itself, so that there is no danger of their being operated independently of the web roll.

Although I have illustrated and described 70 only a single form of the invention and shown it as applied to a particular machine, I am aware of the fact that the cam 10 can be used with the cam 5 shown in my above mentioned case, that the cam 5 shown herein 75 can be used without the cam 10, and that modifications can be made therein by any person skilled in the art without departing from the scope of the invention as expressed in the claims, and that it can be applied in 80 connection with other forms of web roll controlling devices.

Therefore, I do not wish to be limited in these respects, but what I do claim is:—

1. In a web renewing device, the combination of means for pressing the web against a fresh web roll, a stop in position to prevent the pressing means from causing the web to engage the fresh web roll, and means controlled by the fresh web roll for automatically releasing the stop and permitting the pressing means to move toward said roll. 85

2. In a web renewing device, the combination of a roller for pressing an expiring web against a fresh web roll, yielding means for 95 moving the roller toward the fresh web roll, a stop in position to prevent the roller from causing the web to engage the fresh web roll, and electro-magnetic means movable with the fresh web roll for releasing the 100 stop and permitting the yielding means to force the roller to apply the web to the fresh roll.

3. In a web renewing device, the combination of a roller movably mounted, yielding 105 means for forcing said roller toward a fresh web roll, a stop in position to limit the motion of the roller in that direction, means for holding the stop, a cam carried by the fresh web roll, and means operated by said cam 110 for releasing said stop holding means.

4. In a web renewing device, the combination of a movably mounted web controlling roller, a catch, connections normally held by said catch for releasing said roller, a fresh 115 web roll having a projection upon its surface, means operated by said projection for releasing said catch, and means for then operating said connections to allow the roller to move to apply the web to the fresh web roll. 12

5. In a web renewing device, the combination of a movable web controlling roller, a fresh web roll having a circumferential slit through the web on the outside of the roll, a cam having a flange inserted through the 12 slit so as to be carried by the fresh web roll, means for moving the roller to apply the expiring web to the fresh web roll, and means operated by said cam for permitting the last named means to act. 13

6. In a web renewing device, the combination of a movable web controlling roller, a fresh web roll, a cam carried by the fresh web roll, means for moving the roller to apply the expiring web to the fresh web roll, and means operated by said cam for permitting the last named means to act.
7. In a web renewing device, the combination of a movable web controlling or pasting roller, a fresh web roll having a projection upon its surface, a shaft having two arms thereon projecting from the shaft in substantially the same direction, said arms having electrical contacts thereon, yielding means for holding said arms apart, one of the arms being adapted to be engaged by said projection and moved so as to bring said contacts together, and electrical connections controlled by said contacts for setting the pasting roller into operation.
8. In a device of the character described, the combination of a shaft, said shaft having two arms extending therefrom, one loosely mounted, each arm having a contact thereon, a spring for holding said contacts apart, each of said arms having a roller thereon, a web roll in position to receive the rollers on said arms, said web roll having a projection in the path of one of said rollers, whereby when the projection engages that roller its arm will be moved and the contacts brought together, an electro-magnet connected to be energized when said contacts are brought together, a catch controlled by said electro-magnet, an oscillatable member normally held in a certain position by said catch, and means for pressing an expiring web against said fresh web roll, said means being controlled by said oscillatable member.
9. In a device of the character described, the combination of a shaft, said shaft having two arms extending therefrom, each arm having a contact thereon, a spring for holding said contacts apart, a web roll in position to receive the ends of said arms, said web roll having a projection in the path of one of said ends, whereby when the projection engages that end its arm will be moved and the contacts brought together, an electro-magnet adapted to be energized when said contacts are brought together, a catch controlled by said electro-magnet, an oscillatable member normally held in a certain position by said catch, and means for severing an expiring web controlled by the oscillatable member.
10. In a web renewing device, the combination of means for severing an expiring web from its roll, with a movable member, a catch for holding the movable member in a position to prevent the action of the sever-

ing means, and means mounted on the fresh web roll independently of its shaft for releasing the movable member to allow the severing means to operate.

65

11. In a web renewing device, the combination of means for severing an expiring web from its roll, with an oscillatable member for controlling the severing means, a catch for holding the oscillatable member in a position to prevent the action of the severing means, means movable with the fresh web roll for releasing the oscillatable member to allow the severing means to operate, a cam movable with the fresh web roll, and means whereby when said oscillatable member is released said cam will control it and operate it.

70

12. In a web renewing device, the combination of means for severing an expiring web from its roll, with a cam provided with prongs set into the end of the fresh web roll, and means whereby said cam will control the operation of the severing means.

80

13. In a web renewing device, the combination with a fresh web roll and a cam having prongs thereon and set in the end of the web roll between the layers thereof, of a device for applying the expiring web to the fresh web roll, and means adapted to be operated by said cam for controlling the operation of said web applying device.

85

14. In a web renewing device, the combination with a web roll, of a cam mounted on the fresh web roll independently of its shaft for controlling the web renewing operation, said cam having prongs adapted to be set into the end of the web roll between the layers thereof.

90

15. A cam for a web renewing device having prongs projecting from its surface, whereby it can be secured to the end of a web roll.

100

16. In a web renewing device, the combination with a web roll, of a cam mounted thereon independently of the shaft of the web roll for controlling the web renewing operation.

105

17. A web roll having a cam supported on its end independently of its shaft.

110

18. A web roll having a cam on its convex surface for starting the operation of renewing the web.

19. A web roll having a slit through its outer layers and a cam inserted in said slit and projecting from the surface.

115

20. A cam for a web roll having a cam surface and provided with a thin flange adapted to be set into a slit in a web roll.

120

In testimony whereof I have hereunto affixed my signature.

HENRY A. WISE WOOD.
